(57) **CLAIM**

The ornamental design for a light-emitting diode unit for illuminating an object, as shown.

DESCRIPTION

FIG. 1 is a perspective view of a light-emitting diode unit for illuminating an object in accordance with the present design, as viewed from above;

FIG. 2 is a perspective view thereof, as viewed from below;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.
